Term of patent 14 years

(Cl. D56—4)

FIG. 1

FIG. 2

FIG. 5

FIG. 3

FIG. 4

FIG. 6

FIGURE 1 is a left side, top and front perspective of a portable radio, showing one form of my new design wherein the carrying handle is of a particular novel configuration;

FIGURE 2 is a left side elevational view of the form shown in FIGURE 1 with the carrying handle in carrying position, the opposite side being substantially a mirror image thereof;

FIGURE 3 is a top plan view of the form shown in FIGURE 1 with the carrying handle in retracted position;

FIGURE 4 is a front elevational view, to an enlarged scale, of a portable radio, showing another form of my new design wherein the carrying handle is plain and unornamented;

FIGURE 5 is a right side elevational view, to a reduced scale, of the form shown in FIGURE 4, the left side being substantially a mirror image thereof; and

FIGURE 6 is a fragmentary front, top and right side perspective view, partly in cross-section, showing the configuration of the grille in both forms of my new design.

The back and bottom of both embodiments of my design are plain and unornamented.

The broken line showing of legible matter in FIGS. 1 and 4 is for illustrative purposes only.

I claim:

The ornamental design for a portable radio, substantially as shown and described.
